UNITED STATES PATENT OFFICE.

WALTER A. NIVLING, OF ARLINGTON, MASSACHUSETTS.

SIZING-TANK REGULATOR.

1,191,216.

Specification of Letters Patent. Patented July 18, 1916.

Application filed December 22, 1914. Serial No. 878,581.

To all whom it may concern:

Be it known that I, WALTER A. NIVLING, a citizen of the United States, residing at Arlington, in the county of Middlesex and 5 State of Massachusetts, have invented a new and useful Sizing-Tank Regulator, of which the following is a specification.

This application embodies an apparatus shown in my copending application No. 10 823,189 for Letters Patent on a sizing process.

The present application discloses a novel means whereby any desired level may be maintained in a size box, and whereby said levels may be altered at the will of an operator.

As a preliminary statement it will be understood that sizing of the thread or yarn which is used in the manufacture of cotton cloth is necessary in order to strengthen the 20 yarn or thread and to lay the fibers, whereby the material is adequately and properly prepared for the weaving operation. Under the ordinary procedure, a quantity of sizing material sufficient to bring about the desired 25 depth and to secure a maximum sizing efficiency is run into the size box. As the level of the size falls, new size is added occasionally and as a result the maximum depth of sizing material and conditions which 30 promote a maximum efficiency prevail for a short time only, and at times, the sized threads are wholly unsuited for the operation of weaving, due to the failure to restore a proper depth of sizing material soon 35 enough, and due to the fact that the depth of the sizing material in the size box is constantly fluctuating and may fall too low.

The amount of sizing material taken up by the yarn or thread depends upon several 40 factors, to wit, the density of the sizing solution, the character of the material used as a sizing, the tension of the material which is being sized, the twist thereof, the diameter of the yarn, thread or other material, and 45 the depth of the submergence as well as the time during which the yarn or other material is kept submerged, either from the rate of travel of the material to be sized, the depth of the sizing material, or both. A 50 fluctuating depth of size, therefore, affects the length of time during which the yarn is permitted to absorb the sizing material.

One object of the present invention, therefore, is to provide means whereby the depth 55 of the size may be kept constant and the size

kept at a constant consistency between the times of changing the levels.

A further object of the invention is to provide means whereby, simultaneously with the maintenance of a constant level, the 60 heavier portions of the size at any predetermined distance from the bottom of the box are removed.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 is a sectional view partly in elevation, and 75 illustrating diagrammatically, one form of sizing apparatus wherewith the constant level device forming the subject matter of this application has been assembled; Fig. 2 is a section through one of the size boxes; Fig. 3 is an elevation showing one form of constant level device; Fig. 4 is a vertical longitudinal section through the constant level device depicted in Fig. 3; Fig. 5 is a transverse section on the line 5—5 of Fig. 3; Fig. 6 is an elevation showing a portion of the gate, parts being broken away and sectioned; Fig. 7 is a vertical sectional detail illustrating a modified form of constant 80 level device; Fig. 8 is a side elevation showing the modified structure delineated in Fig. 7, parts being broken away; Fig. 9 is a transverse section of the structure shown in Figs. 7 and 8; Fig. 10 is a detail illustrating a portion of the actuating plunger; Fig. 11 is a perspective detail illustrating a portion 85 of the clamping and guiding mechanism; Fig. 12 is a vertical section showing a modified form of constant level device; Fig. 13 is a vertical section on the line 13—13 of Fig. 12; Fig. 14 is a top plan of the structure shown in Fig. 12, the lid being removed; Fig. 15 is a fragmental perspective 90 illustrating the supplemental gate.

In the accompanying drawings and referring to Fig. 1 which is applicable to all of the various constant level devices herein-after described, the numeral 1 indicates a size box of any approved construction, the numeral 2 indicating the material which is 100

to be sized. Any suitable means may be provided for guiding the material 2 through the size box 1. As an illustration there is depicted in Fig. 2, a guide roller 3 journaled for rotation adjacent one end of the size box, a vertically adjustable immersion roller located within the size box, supporting rollers 5, located within the size box, and heavy compression rollers 6 coöperating with the supporting rollers 5, the compression rollers 6 being provided with yieldable facings 7. The material 2 which is to be sized passes over the top of the guide roller 3, beneath the immersion roller 4 and between the compression rollers 6 and the supporting rollers 5. These details, however, may be changed without jeopardizing the utility of the invention, it being necessary merely that the material 2 be guided through the size box by some suitable means. If desired, a storage tank 25 may be provided and across the tank 25 may be extended a screen 26. The storage tank 25 may be equipped with any approved means for heating the size, said means being indicated by the reference characters 25^a. Leading from the storage tank 25 is a supply pipe 27 having a branch 29 for each size box 1 the branches 29 being equipped with valves 30. A pipe 31 communicates with nipples 12 of casings 8 constituting parts of constant level devices to be described in detail hereinafter. The pipe 31 may discharge into the storage tank 25 above the screen 26. In the pipe 31 may be interposed a pump 28. The size may be renewed in any suitable manner, as from a size preparation kettle 32 having suitable means indicated at 33 for discharging into the tank 25, the size preparation kettle being equipped with a heating means 32^a of any desired sort.

The foregoing description sets forth one of the many sizing systems with which any of the constant level devices hereinafter described may be used.

In the present embodiment of the invention there is provided a plurality of constant level devices, one of which is shown in Figs. 3, 4, 5 and 6.

The constant level device under discussion includes a tubular casing 8 comprising laterally separable parts 9 having mating ears 10 through which securing elements 11 pass. Adjacent their lower ends, the constituent parts of the casing 8 are equipped with lateral nipples 12 hereinbefore mentioned, and affording a connection between the casing 8 and the pipe 31. In the interior of the parts 9 of the casing 8 and adjacent their longitudinal edges, upright ribs 14 are formed, the same constituting a guide in which a vertically slidable imperforate gate 15 is mounted. Extended transversely of one of the parts 9 of the casing 8 into close contact with the vertically slidable gate 15 is a plat-

form 16. Located above the platform 16 is a nipple 17 receiving a pipe 18 which enters the size box 1 at or above the bottom thereof. Mounted detachably upon the upper end of the casing 8 by threading or otherwise is a cap 19 which may carry a pet cock 20. A hand wheel 21 or like device is mounted for rotation in the cap 19, as shown at 22. Threaded into the hand wheel 21 is a screw 23 through the lower end of which a connecting element 24 passes, the connecting element 24 being mounted in the upper end of the gate 15.

In practical operation, the heavier and excess portions of the size, lying lower than the surface, pass through the pipe 18 into the casing 8 and are prevented from flowing downwardly by the partition 16. The size rises and flows over the upper edge of the gate 15 and thence passes downwardly into the pipe 31 and from the pipe 31 into the storage tank 25. From the storage tank 25 or from any other suitable source of supply, fresh size is delivered into the size box 1 and when the storage tank 25 is used, fresh size enters the boxes by way of the pipes 27 and 29. The size may be renewed from the size preparation kettle 32.

From the foregoing it will be observed that the heavier portions of the size are drawn away and simultaneously a constant level is maintained in the size box.

It is possible to vary the level of the size in the size box 1 by rotating the hand wheel 21, which, engaging the screw 23, serves to raise and lower the gate 15. Thus, the depth of submergence of the material 2 may be regulated. Through the instrumentality of the mechanism above described, the size is maintained at a constant level and the heavier portions of the size are drawn away, the size thus being kept in a homogeneous condition.

Referring to that form of the invention which is depicted in Figs. 7, 8, 9, 10 and 11, there is shown a casing 50 of tubular form and comprising separable parts 51, recessed as shown at 52 to form webs 53 united by securing elements 54. The parts 51 of the casing 50 are provided with nipples 55 receiving a pipe 56 corresponding to the pipe 31. In the interior of the parts 51 of the casing 50 and along their meeting edges, ribs 57 are formed, the same defining guides in which is mounted to reciprocate a gate 58. Extended transversely of one of the parts 51 of the casing 50 is a platform 59, the gate 58 being adapted to slide in close and intimate contact with the inner edge of the platform 59. Projecting from one of the parts 51 of the casing 50 is a pipe 60 which forms a communication with the size box. The upper end of the casing 50 may be closed if desired as shown at 61, a pet-cock 100 being provided. This pet-cock, like the cock 20,

acts as a vent and prevents the pump 28 from withdrawing too much size and altering the constant level or volume. In the lower edge of the gate 58 there is formed a 5 notch 62.

The means for controlling the movement of the gate 58 includes a plunger 63, offset as shown at 64 adjacent its upper end, the end 64 of the plunger being united by means 10 of a securing element 65 with the lower edge of the gate 58. The offsetting of the plunger as shown at 64 serves to prevent the plunger from spacing the gate 58 apart from the inner edge of the platform 59, and consequently 15 a close closure is effected between the platform and the gate. The lower end of the casing 50 is equipped with a nipple 66 carrying a packing gland 67 through which the plunger 63 passes.

20 The invention comprises a tubular standard 68 threaded at 69 into a socket 70 secured to the floor 71 or to any other accessible support. In opposed portions of the tubular standard 68 elongated slots 72 are formed. The lower end of the plunger 63 passes inside of the standard 68 and is equipped with an opening 73 through which passes a rod 74 lying in the slots 72 and carrying wing nuts 75 adapted to bear against 25 the outer face of the standard 68. One wing nut is threaded onto the rod 74 and the other wing nut is fixed to or integral with the rod. Tubular guides 76 are mounted on the rod 74 and engage the inner surface of the 30 standard 68.

Owing to the fact that the standard 68 is threaded at 69 into the socket 70, the standard may be raised and lowered by rotating the same, thereby permitting an adjustment 40 of the packing gland 67.

The gate 58 may be raised and lowered by loosening the movable wing nut 75, the rod 74 moving in the slots 72 of the standard 68.

Obviously, the level of the size in the size 45 box and the volume of size in the size box is determined by the position of the upper edge of the gate 58. When the gate is raised as shown in Fig. 7 until the upper edge of the notch 62 lies above the upper face of the 50 platform 59, a complete drainage of the size box may be effected.

Passing to that form of the invention shown in Figs. 12, 13, 14 and 15 there is disclosed a casing 200 open at the top but 55 normally closed by means of a lid 201, held in place upon the casing 200 by means of hinges 202 or in any other desired manner. If desired, the casing may be equipped with a pet-cock 222, the functions of which have 60 been alluded to hereinbefore. The casing 200 is provided with a connection 204 adapted to enter into the size box. In opposed relation to the connection 204 is a pipe 205 in which is interposed a valve (not shown). 65 The pipe 205 normally is closed and need not

be considered further, saving for the statement that at times, the pipe 205 may be employed to drain one side of the casing. The outlet pipe from the casing 200 is shown at 70 206 and is adapted to communicate with the pipe 31.

Extended transversely of the casing 200 between the inlet 204 and the outlet 206 is an upright partition 207 provided in its upper edge with a notch 208 and having an opening 209 in its bottom. Upon one side of the partition 207, guide ribs 210 are formed, the same receiving a vertically slidable supplemental gate 211 controlled by an upright rod 212 or the like, the rod having a lateral 75 operating handle 214. Upon the opposite face of the partition, ribs 215 are formed, the same receiving slidably, a main gate 216 having an outstanding lug 217 into which a screw 218 is threaded as shown at 219, the 80 lower end 220 of the screw bearing on the bottom of the casing, and the upper end of the screw being squared as shown at 221, to receive a wrench or key.

Under normal working conditions, the 85 supplemental gate is moved downwardly to close the opening 209 in the bottom of the partition 207 and through the medium of the screw 218, the main gate 216 is raised and lowered so that its upper edge occupies a 90 predetermined position above the lower end of the notch 208 in the partition 207, as shown in Fig. 13. The size enters the casing 200 by way of the connection 204, rises in the compartment at the right hand side 100 of the partition 207, flows through the notch 208 over the upper edge of the main gate 216 and passes out of the compartment at the left hand side of the casing 200, through the outlet 206. From the foregoing it will 105 be obvious that the main gate 216 when in a fixed position, defines a constant level in the size box, it being possible to vary this level at intervals, by adjusting the main gate.

When it is desired to drain the casing 200, 110 the supplemental gate 211 is raised through the instrumentality of the rod 212 and the size flows away through the outlet 206, thus draining the casing.

Having thus described the invention, 115 what is claimed is:

1. In an apparatus for sizing yarn, a size box; a constant level device comprising a casing including a partition, an outlet, and an inlet communicating with the size box; 120 a gate slidable in the casing and co-operating with the partition to define a level in the size box; means for operating the gate to adjust the level in the size box; and means for guiding the yarn through the size box. 125

2. In apparatus for sizing yarn, a size box; a constant level device comprising a casing including a partition and opposed guides, the casing having an outlet and being provided with an inlet communicating with 130

the size box; a gate located between the inlet and the outlet and slidable in the guides, the gate coöperating with the partition to define a level in the size box; means for moving the gate in the guides to adjust the level of the contents of the size box; and means for guiding the yarn through the size box.

3. In a device for sizing yarn, a size box having an outlet opening located at a distance below the desired level of the contents of the size box; a casing having an inlet opening communicating with the outlet opening of the size box and having a discharge opening from which the excess size in the box may flow; adjustable means within the casing for regulating the level of the size within the casing and the box; and means for guiding the yarn through the box at a predetermined distance from the bottom 20 of the box.

4. An apparatus for sizing yarn comprising a receptacle for sizing liquid, means for supplying liquid thereto in excess of the amount used, means for controlling the level of the liquid in the receptacle, said level controlling means comprising a tank having an inlet opening communicating with the receptacle and a discharge opening, a partition across the tank between the inlet and 30 the discharge openings, said partition having an opening at its bottom and also having an opening at a higher elevation, a gate for closing the opening through the bottom of the partition, a second gate for closing the second mentioned opening through the partition, vertical guides for the second gate, a threaded member carried by the gate, an adjusting screw passing through the threaded member and having its lower end in engagement with the tank whereby the gate may be adjusted in its guides or the gate and the adjusting screw may be lifted bodily from the guides; and means for guiding the yarn through the receptacle.

45 5. An apparatus for sizing yarn comprising a receptacle for sizing liquid, means for supplying liquid thereto in excess of the amount required, means for controlling the level of the liquid in the receptacle, said level controlling means comprising a tank having an inlet opening communicating with the receptacle and a discharge opening, a partition across the tank between the inlet and the discharge openings, said partition 50 having an opening at a height somewhat above the bottom of the tank, a gate for closing the opening through the partition, vertical guides for the gate, a threaded

member carried by the gate, an adjusting screw passing through the threaded member 60 and having its lower end in engagement with the tank whereby the gate may be adjusted in its guides or the gate and the screw may be lifted bodily from the guides; and means for guiding the yarn through the 65 receptacle.

6. In an apparatus for sizing yarn, a size box; means for guiding the yarn to be sized through the size box at a predetermined distance from the bottom of the box; and 70 means for maintaining the size in the size box at any desired depth during working periods while the yarn to be sized is passing through the size box, thereby to alter the character of the sized yarn by varying the 75 depth of submergence and the time of submergence.

7. In an apparatus for sizing yarn a size box; means for guiding the yarn to be sized through the size box at a predetermined 80 distance from the bottom of the box; a movable member controlling the level of the size in the size box; and means for holding the movable member in adjusted vertical positions thereby to vary the depth of the size 85 in the size box and to alter the character of the sized yarn by varying the depth of the size and the time of submergence.

8. In a device for sizing yarn, a size box, means for controlling the level of sizing liquid therein, said means comprising an inlet, an outlet located below the desired level of the liquid therein, means for closing the outlet at will, another outlet located at substantially the desired level of the liquid, 85 adjustable means for determining the level of the last named outlet and means for guiding the yarn through the box at a predetermined distance from the bottom of the box.

9. In an apparatus for sizing yarn, a size 100 box, means for controlling the level of sizing liquid in the box said means including an inlet, an outlet, a partition located between the inlet and outlet, a gate movable with reference to the partition to define the 105 level in the size box, means for moving the gate to adjust the level of size in the size box and means for guiding the yarn through the size box.

In testimony that I claim the foregoing as 110 my own, I have hereto affixed my signature in the presence of two witnesses.

WALTER A. NIVLING.
